SOAP SUDS OR LATHER DISPENSING DEVICE

BACKGROUND OF THE INVENTION

1. Field Of The Invention

The present invention relates in general to dispensing devices, more particularly to a soap dispensing device, adapted to dispense soap in the form of suds or lather. Such devices may have industrial or household use for attachment to a water line, faucet, showerhead, washing brush or the like, so that water under pressure is allowed to flow through the dispenser when activated to mix with the soap in the dispenser to produce soapy water, soap suds, or lather.

2. Description Of The Prior Art

Soap or suds dispensers of the above kind are known in the art and generally consist of an attachment to be added to a water line or faucet, but these mostly require modifications in the plumbing or special fittings for attachment to a faucet, and generally use water pressure produced suction to draw soap into the water stream in an uncontrolled fashion. Further, in most cases, water is not effectively blocked from entering the soap chamber, where it dilutes the soap.

In addition, the known devices are bulky and often of complicated structures, especially if it is desired to produce foam rather than only a soap-water mixture. In many instances, an intricate valving arrangement and mechanically driven agitators are employed in order to produce the desired amount and density of soap suds or lather.

SUMMARY OF THE INVENTION

In order to overcome the disadvantages of the prior devices, the present invention provides a novel soap suds or lather dispensing device of relatively simple construction which can be easily attached to any conventional industrial or domestic water outlet without modification to the plumbing, and without requiring any appreciable amount of space.

The novel soap suds or lather dispensing device herein described comprises a container adapted to be filled with soap and which has a water inlet and a mixing chamber enclosed therein normally closed to the soap supply. A manually operable valve is provided to establish communication with the water inlet to introduce a predetermined charge from the soap supply into the mixing chamber and to allow water under pressure to enter the mixing chamber. The mixing chamber is provided with aerating means and a meshlike material which causes the soap and water liquid mixture to convert into suds or lather which then flows out of the dispenser through an opening connected with the mixing chamber.

The invention will be better understood by referring to the following detailed description in connection with the appended drawings which illustrate the preferred embodiment of the invention.

BRIEF DESCRIPTION OF DRAWINGS

FIG. 1 is a side elevation of the present novel lather dispensing device;

FIG. 2 is a cross section through the novel suds or lather dispensing device of FIG. 1 along line 2-2 thereof showing the mixing chamber arrangement;

FIG. 3 is another cross section through the novel dispensing device of FIG. 1 along the line 3-3 thereof, showing the actuating valve structure in an inactive position;

FIG. 3a is a view similar to FIG. 3 showing the valve in activated position;

FIG. 4 is a longitudinal cross section through the novel dispensing device taken along line 4-4 of FIG. 2;

FIG. 4a is an enlarged partial cross section through the mixing chamber and soap injecting means;

FIG. 5 is a side elevational view of the present novel lather dispensing device similar to FIG. 1 showing the other side of the dispenser;

FIG. 6 is a perspective illustration of an installation arrangement for the present novel soap suds or lather dispenser;

FIG. 7 is another perspective illustration of a different installation arrangement of the present novel soap suds or lather dispenser;

FIG. 8 is still another perspective illustration of a further different installation arrangement for the present novel soap suds or lather dispenser.

DESCRIPTION OF THE PREFERRED EMBODIMENT

With reference to FIGS. 1-5, the present novel soap suds or lather dispensing device comprises a housing 10 which may be round or any other shape as desired. A round housing is shown in the drawings for illustrative purposes. The housing 10 is preferably composed of a first cylindrical housing section 12 and a second cylindrical housing section 14 which are open-ended and have mating circumferential wall surfaces to be placed together as a unit as shown in FIG. 4. In the assembled position, the two open-ended cylindrical housing sections 12 and 14 are placed together and the opposite open ends are closed by plates 16 and 18 respectively to completely close the structure. The two cylindrical housing sections 12 and 14 and closure plates 16 and 18 are secured in their assembled positions by means of bolts 20 or the like which extend through the closure plates and through complimentary aligned bosses 22 on the internal wall surfaces of both cylindrical housing sections 12 and 14 as seen in FIG. 4. Suitable gaskets (not shown) will normally be placed between the adjoining surfaces of the housing sections 12 and 14 and closure plates 16 and 18 to prevent leakage of liquid from the housing 10.

With particular reference to FIGS. 2 and 3, the cylindrical housing sections 12 and 14 are each provided internally with mating integral boss portions 24 and 24a extending from the lower inner surface of the housing walls transversely through the housing sections towards their axial center to form, in assembly, a unitary boss structure. The internal boss structure 24-24a is substantially cylindrical around the axis center of the housing section and is connected with the housing walls by enlarged portions 26 and 26a respectively. The space between the internal boss structure 24-24a and the housing walls of the housing sections 12 and 14 form a chamber 28 adapted to be filled with liquid soap after the housing has been assembled through a removable filler plug 30 at the top of the housing section 12 which is preferably provided with an air vent 31.

The cylindrical part of the internal boss structure 24-24a is provided with a central axial bore 32 adapted to receive a cylindrical valve member 34 in the form of a shaft for rotation therein by means of a lever 36 formed integral with the valve member 34 and which extends out of the housing section 14 through a flared aperture 38 provided therein. The flared lever aperture 38 has a front side wall 40 and an opposite rear side wall 42 positioned angularly thereto in order to limit the angular movement of the lever 36 to define an inactive position as in FIG. 3 and a dispenser activating position as in FIG. 3a. The cylindrical valve member 34 is axially bored through to provide a bore 44 which is adapted to be in communication at both ends, with the bores 46 and 48 respectively of pipe fittings 50 and 52 (shown in FIG. 4) which are attached by any known means to the closure plates 16 and 18 for connection of the dispenser to any conventional water pipe or water outlet as illustrated in FIGS. 6-8. Thus, in the inactive position of the dispenser when attached to a water outlet, water will be permitted to flow unrestricted from the outlet through the central bore 44 of the valve member and out of the dispenser.

For actuation of the suds or lather dispenser, the valve member 34 is provided with a transverse bore 54 extending from the axial valve bore 44 to the surface of the valve member and which is adapted in activated position of the valve as in FIG. 3a to be in communication with a radial channel 56 through a passage 57 provided within the cylindrical boss portion 24-24a around the central bore 32. With particular reference to FIG. 2, which shows the valve member 34 in an activated position, the radial channel 56 is connected 75 within the housing section 12 through a passage 58 with a mix-

ing chamber 60 provided in the enlarged boss portion 26 which is closed to the outside by a screw plug 62 provided with a seal 64. Contained at the other end of the mixing chamber 60 and suitably secured therein is an assembly of porous or meshlike material 66 through which the mixing chamber 60 is connected to the outlet 68 extending through the boss portion 26 out of the housing section 12. A plurality of air induction vents 70 (FIGS. 2 and 5) are provided through the boss portion 26 to connect the mixing chamber with the atmosphere for a purpose to be explained. As thus far described, if the valve member 34 is rotated into the position shown in FIG. 2, water from the water outlet to which the dispenser is being attached will be diverted from the unrestricted flow through the valve bore 44 into the transverse bore 54 and from there into the radial channel 56. The water, being under pressure, will then be expelled through the passage 58 into the mixing chamber 60 from which it travels through the mesh assembly 66 out of the housing outlet 68.

In order to produce soap suds or lather, the housing section 14 of the dispenser 10 is provided with the following arrangement activated by the valve lever 36: With particular reference to FIGS. 3, 3a and 6, the valve lever 36 at one side and within the housing section 14 is in sliding engagement with a rod 72 within the lever aperture 38 which is part of a plunger 74 slidably arranged within a cylindrical plunger chamber 76 within the enlarged boss portion 26a of the internal boss structure 24a in the housing section 14. The cylindrical plunger chamber 76 is closed to the outside by a screw plug 78 which is sealed as at 80. A spring 82 between the plunger 74 and screw plug 78 tends to bias the plunger outwardly away from the screw plug thereby exerting force on the lever 36 to return and maintain the lever 36 in the normal inactive position as shown in FIG. 3. The plunger chamber 76 is in normally open communication with the soap containing chamber 28 by means of an aperture 84 through the wall 86 of the plunger chamber by which this chamber is constantly supplied with liquid soap from chamber 28. The plunger chamber 76 has another aperture 88 which is spaced and angularly offset from the first aperture 84 towards the rear of the chamber. Aperture 88 is adapted to establish communication through a passage 89 with the mixing chamber 60 in the housing section 12 in assembled position of both housing sections and upon activation of the valve lever 36. As seen in FIG. 4a, the aperture 88 is normally closed by a one-way check valve 90 which, however, upon pressure applied by the plunger 74 opens to permit the injection of liquid soap from the plunger chamber 76 into the mixing chamber 60. The one-way check valve 90 prevents back flow of water from the mixing chamber into the soap containing plunger chamber 76.

In operation, and with the dispenser attached to a water outlet by fitting 50 or 52, water flows into the dispenser from the side where it is attached to the water outlet into the central bore 44 of the valve member 34. Upon rotation of the valve member by manipulation of the valve lever 36 from the inactive position as shown in FIG. 3 to the position shown in FIG. 2 and 3a the flow of water will be diverted through the transverse bore 54 into the radial channel 56 and from there through the passage 58 into the mixing chamber 60. Simultaneously, as the water is being diverted to flow into the mixing chamber 60 the annular movement of the lever 36 causes movement of the plunger 74 into the plunger chamber 76 against the force of the spring 82 which will be compressed. Pressure within the plunger chamber 76 forces the liquid soap contained in the chamber through the aperture 88 thereby opening the one-way valve 90 to allow the liquid soap to pass and be injected under pressure into the mixing chamber 60 where the soap is then mixed with the water supplied from the radial channel 56. Movement of the plunger 74 into the chamber 76 causes immediate closure of the supply aperture 84 by the plunger to prevent any feedback of the soap into the soap chamber 28 and to provide only a predetermined quantity of soap for mixing. The water pressure in the mixing chamber 60 forces the water-soap mixture through the mesh

66 where air is sucked into the mixing chamber through the air vent 70 for aeration of the mixture. This combined agitation by which the water-soap mixture is forced through the mesh 66 and aerated by vents 70 causes suds or lather to be produced at the other end of the mesh 66 which is then expelled through the outlet 68. Instead of the provision of vents 70, air can be received directly through the outlet 68. It will be seen that the amount of water and liquid soap being expelled into the mixing chamber 60 can be metered as desired by the amount of movement of the valve lever 36 from the inactive position in FIG. 3 to the maximum active position in FIG. 3a. Any intermediate position of the valve lever 36 permits a less than maximum metered amount of water and liquid soap to enter the mixing chamber 60.

10 Release of the lever 36 causes expansion of the spring 82 in the plunger chamber 76 forcing the plunger outwardly and thus returning the valve lever 36 to its inactive position as in FIG. 3. By return of the valve lever, the valve member 34 is rotated in reverse direction to move the transverse bore 54 away from the radial channel opening 57 thus stopping the water supply for the mixing chamber by blocking the radial channel 56. At the same time, as the pressure in the plunger chamber 76 is being reduced, the one-way valve 90 closes the aperture 88 to prevent water, still remaining in the mixing chamber 60, from entering the plunger chamber 76 and to prevent any leakage of soap through the opening 88. Upon complete return of the plunger 74, the supply aperture 84 will again be opened to permit liquid soap from the soap chamber 28 to enter the plunger chamber 76.

20 With particular reference to FIG. 2, an auxiliary soap injection means is provided by an auxiliary plunger assembly 92 if it is desired to bypass the lather producing mixing chamber 60 to provide only a water-soap mixture through the central valve bore 44 from the water pipe to the water outlet without producing suds or lather, or to pass the soap-water mixture through a shower head to produce lather. The auxiliary plunger assembly 92 is contained within a cylinder 94 substantially contained within and preferably integral with the housing section 12. The cylinder 94 extends from the wall of the housing section 12 across the soap chamber 28 to the central cylindrical boss portion 24 to be preferably integral therewith as shown. The cylinder 94 has a through bore 96 which extends to the valve member 34 to be normally in communication with the transverse passage 54 of the valve member when the valve lever 36 is in its inactive position as in FIG. 3. The outer end of the cylinder bore 96 is closed by a screw plug 98 which has a central aperture 100 to receive a plunger 102 that extends a distance out of the screw plug. The inner end of the plunger 102 is connected to a piston 104 adapted for movement within the bore 96 by depression of the plunger 102. The piston 104 is normally biased in an outward direction by a spring 106 which is supported within the bore 96 on a plate 108 retained against a shoulder 110 within the bore 96. The plate 108 has a central valve opening 109 which is normally held closed within the cylinder. The space between the piston 104 and the plate 108 defines a spring chamber 112 which is normally in open communication with the soap chamber 28 by means of an opening 114 in front of the piston 104 to supply the spring chamber with liquid soap.

30 Thus, by depression of the plunger 102, the piston 104 is forced inwardly thereby closing the opening 114. The pressure created in the soap filled spring chamber 112 by inward movement of the piston 104 causes the valve 109 to crack open to permit the injection of a charge of liquid soap into the water contained in the cylinder bore 96 to mix with the water for outflow through the central valve bore 44. Any amount of liquid soap can be injected into the water flow by pumping the plunger 102.

40 With reference to FIG. 6, the present novel dispenser is shown attached to a T-connector 116 of a water pipe 118 by means of its fitting 50. In this installation, the outlet of the other dispenser fitting 52 will be closed by a plug 120. Due to 50 the water pressure in pipe 118 the water flows into the central

valve bore 44. When the valve lever 36 is manipulated, water will be permitted to enter the mixing chamber 60 to mix with the soap therein to produce suds or lather which will be dispensed through the outlet 68 at the bottom of the dispenser, as described above.

In the arrangement in FIG. 7, the dispenser is attached to a water outlet 122. The front fitting 52 receives a conventional shower head 124. If the water has been turned on, it will flow from the outlet 122 through the dispenser by means of the central valve bore 44 and out through the shower head in a normal manner. If the auxiliary plunger 102 is depressed, an amount of liquid soap will be injected into the water flow in the manner above described to exit as a water-soap mixture through the shower head 124. If soap suds or lather are desired, the valve lever 36 is manipulated to produce suds or lather in the manner before described and without interruption of the water flow through the shower head 124. Soap suds or lather can also be produced without turning the shower faucet on due to the residual water pressure in the water outlet 122. If warm or hot water is being used, the dispenser will be preheated and will produce warm soap suds or lather upon activation of the dispenser.

In the arrangement in FIG. 8, the dispenser is attached to a water pipe 126 and the front fitting 52 receives a faucet 128 having a valve handle 130. If the faucet 128 is opened by manipulation of the handle 130, water will flow unrestricted through the dispenser and out of the faucet. Either auxiliary plunger 102 or valve lever 36 may be actuated to expel a water-soap mixture through the faucet or to independently produce soap suds or lather as described. Here, likewise, if warm water is being used, the dispenser will be preheated to produce warm suds or lather.

In summary, the present novel soap suds or lather dispenser is of relatively small size and lightweight when made of aluminum. Its construction and operation is substantially foolproof and needs little or no maintenance.

The construction is such as to be easily attached to any conventional water outlet without any alteration to the plumbing. The present novel soap suds dispenser is powered by water pressure alone to mix liquid soap and water to produce a soap-water mixture, suds or lather.

The present invention may be embodied in other certain forms without departing from the essential characteristics thereof, and therefore the present embodiments are to be considered in all respects as illustrative only and not restrictive, the scope of the invention being indicated by the appended claims rather than by the foregoing description.

I claim:

1. A soap or lather producing device for attachment to a water outlet and comprising a mixing chamber and a soap injection means, a soap supply means in communication with said soap injection means, means to selectively connect said mixing chamber with said water outlet; said soap injection means comprising a chamber, a plunger in said chamber, a normally closed passage connecting said chamber with said mixing chamber; and means to apply force to said plunger to inject a charge of soap of a predetermined amount into said mixing chamber through said normally closed passage when said mixing chamber is connected to said water outlet.

2. In the soap suds or lather producing device as claimed in claim 1, said means to selectively connect said mixing chamber with said water outlet comprising a valve having a first position blocking the flow of water through said water outlet and a second position connecting said water outlet with said mixing chamber to permit water to enter said mixing chamber.

3. In the soap suds or lather dispensing device as claimed in claim 2, said valve being provided with a lever for actuation thereof.

4. In the soap suds or lather dispensing device as claimed in claim 3, said means to apply force to said plunger comprising the aforesaid lever.

5. In the soap suds or lather dispensing device claimed in claim 1, said mixing chamber having an outlet for dispensing lather, and aerating and mixing means within said mixing chamber to produce lather upon connection of said mixing chamber with said water outlet and injection of soap into said mixing chamber.

6. In the soap suds or lather dispensing device claimed in claim 1, said normally closed passage including a one-way valve in the direction from said plunger chamber to said mixing chamber.

7. In the soap suds or lather dispensing device claimed in claim 1, means associated with said soap injection means to block said soap supply upon application of force to said plunger.

8. A soap suds or lather dispensing device comprising a housing having a water inlet for attachment to a water supply, a first chamber in said housing adapted to be filled with soap, a second chamber in said housing separate from said first chamber, a third chamber in said housing separate from said first and second chambers, means to connect said first chamber with said third chamber to supply said third chamber with soap, means to selectively connect said second chamber with said water supply, normally closed valve means associated with said third chamber to establish communication between said third and said second chamber when opened, pressure means in said third chamber adapted to inject soap into said second chamber through said valve means upon selectively connecting said second chamber with said water supply to provide a soap and water mixture in said second chamber, means within said second chamber to agitate said soap and water mixture to produce lather and an outlet for said second chamber to expel said lather from said second chamber and out of said housing.

9. In the device as defined in claim 8, said means to selectively connect said second chamber with said water supply comprising a valve having a central bore communicating with said water inlet and said water outlet and an opening in said valve to connect said central bore with said second chamber upon repositioning of said valve.

10. In the device as defined in claim 9, said valve being confined centrally within said housing for rotation therein by means of a lever attached to said valve.

11. In the device as defined in claim 10, said lever being adapted upon rotation of said valve to simultaneously actuate said pressure means in said third chamber.

12. In the device as defined in claim 11, said pressure means in said third chamber being a plunger connected to said lever and said normally closed valve means being pressure responsive to open under pressure applied by said plunger.

13. In the device as defined in claim 12, said means to connect said first chamber with said third chamber being a normally open passage adapted to be closed upon advancement of said plunger within said third chamber.

14. In the device defined in claim 8, said means in said second chamber to agitate said soap and water mixture being a porous material, and aerating means within said second chamber to cooperate with said porous material to produce lather.

15. In the device defined in claim 14, said aerating means being air injection vents connecting said second chamber with the atmosphere.

16. The device defined in claim 8 further comprising, a fourth chamber separate from said first, second and third chambers and normally in communication with said water supply, a partition plate in said fourth chamber defining a pressure responsive valve means, manually operable pressure means in said fourth chamber and means to supply said fourth chamber with soap from said first chamber between the space defined by said pressure means and said partition plate.

17. In the device as defined in claim 16, said pressure means being a plunger adapted to be depressed to eject said soap through said valve means into said water supply.

18. A soap or lather producing device for attachment to a water outlet adapted to introduce water under pressure into said device, a soap supply in said device, a mixing chamber in said device, means providing a forced injection of a quantity of soap from said soap supply into said mixing chamber, said means comprising a normally closed passage from said soap

supply into said mixing chamber, pressure producing means adapted upon actuation to open said passage, said pressure producing means cooperating with said water under pressure to inject a quantity of soap into said mixing chamber when said water outlet is opened.
